W. J. HAMBLIN.

PIPE WRENCH.

APPLICATION FILED APR. 21, 1914.

1,098,722.

Patented June 2, 1914.

UNITED STATES PATENT OFFICE.

WALTER JAMES HAMBLIN, OF PERTH, WESTERN AUSTRALIA, AUSTRALIA.

PIPE-WRENCH.

1,098,722.

Specification of Letters Patent.

Patented June 2, 1914.

Application filed April 21, 1914. Serial No. 833,464.

To all whom it may concern:

Be it known that I, WALTER JAMES HAMBLIN, a subject of King George the 5th of Great Britain, residing at the city of Perth, 5 in the State of Western Australia, Australia, have invented certain new and useful Improvements in Pipe-Wrenches, of which the following is a full, clear, and exact specification.

10 This invention relates to pipe wrenches, and has for its object to provide such a tool of improved construction capable of operation in either direction and of being reversed without removal from the pipe.

15 Further objects are to strengthen the wrench and make it more sure in its grip upon the pipe without complicating the construction of the tool, and to provide a wrench which will not mark or damage the pipe operated upon in any way.

Other objects will appear as the description proceeds.

The invention will be first hereinafter described in connection with the accompanying drawings, which constitute a part of this specification, and then more specifically defined in the claims at the end of the description.

In the accompanying drawings, wherein 30 the various reference characters represent the same parts in each of the views:—Figure 1 is a side elevation of a wrench constructed in accordance with my invention, part of the handle being broken away. Fig. 2 is an 35 edge view thereof. Fig. 3 is an end view looking at the outer end of the head, and Fig. 4 is a sectional view of the head taken on the line IV—IV of Fig. 2.

The handle A of the wrench is provided 40 at one end with an enlarged head B generally circular in form. A yoke-shaped catch grip C is axially pivoted to the head by means of a pin D. On one side of the head, the lateral faces thereof are cut away, 45 as at E from a point adjacent the handle to a point on the outer portion of the head on the opposite side of the pivot pin D, see Fig. 1. A link or grip F straddles the portion G between the lateral recesses E about 50 midway of the length of said recesses, and is eccentrically pivoted by a pin f with respect to the head at that point, whereby said link or grip F is adapted to swing through an arc of at least 180°. To the outer end 55 of said link or grip there is attached one

end of a chain H having spaced lateral projections K, see Figs. 1 and 3.

The yoke C has a slot or way L cut through its outer end portion which slot or way is substantially equal in width to the chain H. The inner walls of the slot or way L are recessed at M and N to provide catches O adapted to engage the lateral projections K on the chain F to hold said chain about a pipe when the tool is operated, as illustrated in Fig. 1. In this figure the wrench is shown applied to a rather small pipe P, but it will be understood that the tool may be adjusted to fit pipes varying throughout a wide range of sizes. When the tool is operated in one direction the catch grip C comes into play, whereas when the wrench is operated in the opposite direction the link or grip F comes into action. When the catch grip C is in use, the link F serves 75 simply as a part of the chain.

The inner portion R of the head, adjacent the handle, is made eccentric to limit the movement of the catch grip C in one direction. The movement of said catch grip C in 80 the other direction is limited by the link F over which the catch grip C is adapted to swing by reason of the fact that said link is pivotally mounted in the lateral recesses E.

Having thus described my invention, what 85 I claim as new and desire to secure by Letters Patent of the United States is:

1. A pipe wrench having at one end of its handle an enlarged substantially circular head, a catch grip axially pivoted to swing about said head, a link eccentrically pivoted to said head, and a chain secured to the outer end of the link and provided with lateral projections for engaging a recess in the catch grip to lock said chain about a pipe 95 when the tool is operated in either direction.

2. A pipe wrench having at one end of its handle an enlarged substantially circular head, a catch grip axially pivoted to swing about said head, a link eccentrically pivoted 100 to said head, there being an arcuate recess in the lateral face of the head in which the link is pivoted, whereby said link is adapted to swing into the arc of movement of the catch grip, and a chain secured to the outer end 105 of the link and provided with lateral projections for engaging a recess in the catch grip to lock said chain about a pipe when the tool is operated in either direction.

3. A pipe wrench having at one end of its 110

- handle an enlarged substantially circular head, a catch grip axially pivoted to swing about said head and having a concave gripping face, a link eccentrically pivoted to said head, and a chain secured to the outer end of the link and provided with means of adjustable connection with the catch grip to lock said chain about a pipe when the tool is operated in either direction.
- 10 4. A pipe wrench having at one end of its handle an enlarged substantially circular head, a catch grip axially pivoted to swing about said head, a link eccentrically pivoted to said head to swing irrespective of the catch grip and into the same arc of movement therewith, and a chain secured to the outer end of the link and provided with means of adjustable connection with the catch grip to lock said chain about a pipe.
- 15 5. A pipe wrench having at one end of its handle an enlarged substantially circular head, a catch grip axially pivoted to swing about the head, a link eccentrically pivoted to said head, there being an arcuate recess in the lateral face of the head in which the link is pivoted, whereby said link is adapted to swing through an arc of approximately one hundred and eighty degrees, including

part of the arc of movement of the catch grip, and a chain secured to the outer end of the link and provided with means of adjustable connection with the catch grip to lock said chain about a pipe when the tool is operated.

6. A pipe wrench having at one end of its handle an enlarged substantially circular head provided with eccentric portions adjacent the handle, a catch grip axially pivoted to swing about the head, a link eccentrically pivoted to said head within the plane of the catch grip, the eccentric portions of the head serving to limit the swing of the catch grip in one direction and the link limiting its movement in the other direction, and a chain secured to the link and provided with means of adjustable connection with the catch grip to lock said chain about a pipe when the tool is operated.

In testimony whereof I have signed my name to this specification in the presence of two attesting witnesses.

WALTER JAMES HAMBLIN.
